PROCESS FOR ANODIC ESTERIFICATION

Per Valter Öhman, Bromma, Stockholm, Sweden, assignor to Dr. Ing. Mario Biazzini Soc. An., Vevey, Switzerland, a corporation of Switzerland

No Drawing. Application June 7, 1954
Serial No. 435,068

3 Claims. (Cl. 204—80)

This invention relates to a process for anodic esterification in which the anolyte is a solution in an organic solvent and the catholyte is an aqueous solution and the anolyte and the catholyte are separated from one another by a diaphragm. As examples of such esterification may be mentioned the production of nitric acid esters of olefines with the use of calcium nitrate as salt of conductivity and source of supplying NO_3^- . An example of a suitable organic solvent is acetone.

It has been found that in such esterification processes it is possible to obtain a satisfactory current utilization or electrolytic efficiency only under the condition that the effective water content of the anolyte is maintained at a low value. Owing to its composition the anolyte has a high ohmic resistance, while the catholyte, being an aqueous solution, has a low ohmic resistance. In order to prevent leakage of current in too great a degree, the diaphragm must be filled with catholyte as far as possible which theoretically may be effected by maintaining a suitable difference of pressure between the anolyte system and the catholyte system. In practice, however, it is extremely difficult to regulate this difference of pressure in such a way that the water content of the anolyte does not increase in which case, the electrolytic efficiency will rapidly decrease with increasing content of water in the anolyte.

The present invention has for its object to counteract and prevent an increase of the effective concentration of water in the anolyte. For this purpose, according to the invention, the catholyte is brought in contact with or has added thereto a water-binding substance which substantially prevents passage of water from the catholyte through the diaphragm into the anolyte and reduces the effect of this water upon the electrolytic efficiency of the process.

As an example of a suitable water-binding substance may be mentioned calcium nitrate which is suitably added in the form of anhydrous nitrate, for example in an amount of 5–10% by weight, based on the catholyte. Excellent results are obtained, if the addition is regulated in such a way that the content of $\text{Ca}(\text{NO}_3)_2$ in the catholyte amounts to 40% or more. Especially advantageous is an addition of the calcium nitrate in such a quantity that the content of water in the catholyte corresponds to or only slightly differs from that corresponding to the hydrate with the formula $\text{Ca}(\text{NO}_3)_2 \cdot 4\text{H}_2\text{O}$ which composition of the catholyte is made possible, due to the comparatively low melting point of the hydrate in question. This hydrate contains about 69% by weight of calcium nitrate. If required, the melting point may be lowered still more by addition of anhydrous or substantially anhydrous nitric acid as will be seen from the table below:

	Composition	Freezing point, degrees
1.	$\text{Ca}(\text{NO}_3)_2 \cdot 4\text{H}_2\text{O}$	41.0
2.	100 g. $\text{Ca}(\text{NO}_3)_2 \cdot 4\text{H}_2\text{O}$ + 5 g. fuming nitric acid (sp. w. 1.52)	33.4
3.	100 g. $\text{Ca}(\text{NO}_3)_2 \cdot 4\text{H}_2\text{O}$ + 10 g. fuming nitric acid (sp. w. 1.52)	28.3

2

Consequently, according to the invention it is possible to use at a temperature slightly above 41°C . a catholyte consisting solely of the hydrate $\text{Ca}(\text{NO}_3)_2 \cdot 4\text{H}_2\text{O}$ and to lower the temperature, at which the reaction can be carried out, to a temperature under 30°C ., by addition of a moderate amount of anhydrous nitric acid, to said catholyte. From about 2 to 15% by weight no nitric acid can be used in the catholyte. In reality, there would be no danger of crystallization taking place in the diaphragm, even if the anolyte had a considerably lower temperature, since calcium nitrate solutions may be supercooled in a high degree. Moreover, the diaphragm is subjected to a heating electrically which would immediately increase, if the ohmic resistance, due to crystallization, would increase.

The invention is applicable in all cases where esterification can be carried out electrochemically. Preferred examples are the estification of olefines, including pure olefinic hydrocarbons of the type ethylene, propylene, butylene etc. (exemplified by the experimental series described in Example 1 below), olefines having more than one double bond, such as methylpentadiene, butadiene etc. (exemplified in Example 2) and substituted olefines containing a substituent, for example a carboxylic group (exemplified in Example 3). In the examples below the degree of esterification obtained is expressed by stating the amount of nitrogen in g. per ampere/hour which is combined with the ester formed. This is a rough measure of the electrolytic efficiency of the esterification process.

Example 1

In the experiments in this series ethylene was used as primary material. The anolyte has in all cases the following composition:

35 Acetone _____ ml. 100
 $\text{Ca}(\text{NO}_3)_2 \cdot 4\text{H}_2\text{O}$ _____ 5

As anode a platinum wire gauze with a surface of 66 cm^2 was used. The density of current was maintained as near as possible to 3.5 amperes/dm.². The ethylene was added with stirring to the anolyte. Immediately before the commencement of the experiment 20 ml. catholyte was added to the anolyte. This addition was made substantially to simulate the conditions which would result from the passage of the same amount of catholyte through the diaphragm. After 30 minutes the experiments were discontinued. After neutralization by addition of bicarbonate the acetone was evaporated, whereupon the oxidation product formed was extracted with ether.

The following results were obtained:

	Composition of the catholyte added to the anolyte	g. oxidation product per ampere/hour	nitrogen content percent of the oxidation product	g. nitrogen per ampere/hour
55	3.2% $\text{Ca}(\text{NO}_3)_2$ _____ 3.0% HNO_3 _____ 40% $\text{Ca}(\text{NO}_3)_2$ _____ 10% HNO_3 _____ 91% $\text{Ca}(\text{NO}_3)_2 \cdot 4\text{H}_2\text{O}$ _____ 9% HNO_3 _____	1.466 1.610 1.880	15.52 15.48 15.36	0.228 0.260 0.289

The above table shows that the loss of efficiency, due to the addition of catholyte (directly or by penetration through the diaphragm), to the anolyte, is substantially reduced when the catholyte contains at least 40% $\text{Ca}(\text{NO}_3)_2$. This is due to the water binding power of the calcium nitrate.

In the practical operation of my process the procedure outlined above is followed except for omission of the step of adding catholyte directly to the anolyte. The above tests simulate the practical process after it has been oper-

ated for a sufficient time so that 20 ml. of catholyte have passed through the diaphragm into the anolyte.

Example 2

As compound to be esterified in this case methylpentadiene was used. The anolyte had in all cases the following composition:

Acetone	ml.	200
Ca(NO ₃) ₂ .4H ₂ O	g.	10
Methylpentadiene	ml.	10

As anode a platinum wire gauze with a surface of 156 cm.² was used. The density of current was 1.34 amperes per dm.² During a period of 35 minutes 25 ml. catholyte was added to the anolyte. After 30 minutes the experiments were discontinued. After neutralization by addition of bicarbonate acetone and excess of methylpentadiene were evaporated, whereupon the oxidation product formed was extracted with ether.

The following results were obtained:

Composition of the catholyte added to the anolyte	g. oxidation product per ampere/hour	nitrogen content percent of the oxidation product	g. nitrogen per ampere/hour
4.7% Ca(NO ₃) ₂	3.72	3.61	0.134
2.3% HNO ₃			
40% Ca(NO ₃) ₂	3.64	4.18	0.152
10% HNO ₃			
90% Ca(NO ₃) ₂ .4H ₂ O	3.80	3.99	0.152
10% HNO ₃			

Example 3

As compound to be esterified in this case crotonic acid was used. The anolyte had in all cases the following composition:

Acetone	ml.	100
Ca(NO ₃) ₂ .4H ₂ O	g.	1
Crotonic acid	g.	2

As anode a platinum wire gauze with a surface of 66 cm.² was used. The density of current was maintained as near as possible to 3.5 amperes/dm.² Immediately before the commencement of the experiment 20 ml. catholyte was added to the anolyte. After 30 minutes the experiments were discontinued. After neutralization by addition of bicarbonate the acetone was evaporated, whereupon the

mixture was acidified by addition of a small quantity of acetic acid and nitric acid. The oxidation product formed was extracted with ether and then carefully washed with water before evaporation. The following results were obtained:

Composition of the catholyte added to the anolyte	g. oxidation product per ampere/hour	nitrogen content percent of the oxidation product	g. nitrogen per ampere/hour
3.2% Ca(NO ₃) ₂	0.903	8.35	0.075
3.0% HNO ₃			
40% Ca(NO ₃) ₂	1.667	7.04	0.117
10% HNO ₃			
86% Ca(NO ₃) ₂ .4H ₂ O	2.786	4.34	0.121
14% HNO ₃			

What I claim is:

1. In the process of manufacturing nitric acid esters by anodic esterification, making use of a diaphragm cell in which a catholyte comprising an aqueous solution of calcium nitrate is separated by a diaphragm from an anolyte comprising an unsaturated organic compound having at least one double bond between carbon atoms dissolved in an organic solvent therefor and an electric current is passed from an anode in the anolyte to a cathode in the catholyte; the improvement which comprises employing as catholyte an aqueous solution containing dissolved therein at least about 40% by weight of calcium nitrate, sufficient to reduce the decrease in electrolytic efficiency produced by the migration of aqueous catholyte through the diaphragm into the anolyte, and from about 2 to 15% of anhydrous nitric acid, sufficient to reduce the melting point of the catholyte below operating temperatures, whereby a high electrolytic efficiency is obtained which decreases only slowly during the electrolysis.
2. The process of claim 1 wherein the concentration of calcium nitrate in the catholyte ranges from about 40% Ca(NO₃)₂ to 91% Ca(NO₃)₂.4H₂O.
3. The process of claim 1 wherein the catholyte consists of a melt of the hydrate Ca(NO₃)₂.4H₂O containing from 2 to 15% anhydrous nitric acid.
